G. SUNDBACK

SEPARABLE FASTENER SLIDER

Filed May 8, 1923

UNITED STATES PATENT OFFICE.

GIDEON SUNDBACK, OF MEADVILLE, PENNSYLVANIA, ASSIGNEE TO HOOKLESS FASTENER COMPANY, OF MEADVILLE, PENNSYLVANIA, A CORPORATION OF PENNSYLVANIA.

SEPARABLE FASTENER SLIDER.

Application filed May 8, 1923. Serial No. 637,447.

To all whom it may concern:

Be it known that I, GIDEON SUNDBACK, a subject of the King of Sweden, and a resident of Meadville, in the county of Crawford and State of Pennsylvania, have invented certain new and useful Improvements in Separable Fastener Sliders, of which the following is a specification.

This invention relates to separable fastener sliders and has for its object to provide improvements upon the sliders shown in my Patents #1,219,881, dated March 20, 1917, and #1,302,606, dated May 6, 1919, wherein are shown sliders having the actuating means attached on an end thereof.

According to this invention, a rigid pull is transversely pivoted about the center of the slider and preferably to the specially formed head of the rivet which holds the wings together.

Such a construction is adapted to provide a smooth travel for the slider along the stringers; the actuating force applied at about the center or intermediate portion and above the plane of the stringers has an upward component thereof effective to raise the slider instead of raising only one end thereof, as is the case when the pull is attached at the end. This enables the slider to move more easily and smoothly when the actuating force is applied at a central point between the divergent channels. Another advantage accruing from the location of the pull in the center is the provision of surfaces on either side of the pull, lengthwise of the slider against which the operator's fingers may be pressed to steady the movement of the slider and lessen chatter when the pull is held between the fingers, or more precisely by the thumb and forefinger. This invention also comprises a rigid construction of few parts.

Referring to the drawings:

Figure 1 shows the new slider in position controlling the locking members.

Fig. 2 is a side view of the slider alone,

Fig. 3 shows the rivet before being inserted through the slider,

Fig. 4 is a section on the line 4-4 of Fig. 3,

Fig. 5 is a view corresponding to Fig. 1, but showing another form of rivet head,

Fig. 6 is a side view of the device shown in Fig. 5, and

Fig. 7 is an outline of the slider blank before being bent to shape.

The slider 10 of this invention is adapted to be used for similar purposes to the slider illustrated in my Patents #1,219,881 and #1,302,606 above referred to wherein the slider controls the engagement of a number of locking members 11 mounted on stringers 12. The slider is formed from a metal blank having wing portions 13 connected by the neck 14. The wing portions have inturned edges 15 adapted, when bent to the shape illustrated, to provide diverging channels through which the locking members pass and to stiffen the wings. A rivet 16 passes through the wing portions and prevents them from spreading. Before insertion of the rivet the spacer portions 17 are bent down and inserted between the wings to hold them a fixed distance apart when clamped by the rivet. The lower ends 18 of each spacer 17 are bent inwardly as shown in Fig. 1 to form inner walls for the diverging channels. The rivet 16 has a head 19 on one side and a portion 20 on the opposite end adapted to be bent down in clamping the wing portions. Grooves 21 in the rivet head provide means for transversely pivoting the pull device 22 in the intermediate portion of substantially the center part of the slider so that the operator's fingers may steady the surface of the slider longitudinally on each side of the pull device. Within the rivet are guide grooves 23 which form the wedge shaped cross section shown in Fig. 2 with the point of the wedge at the vertex of the diverging channels. Such grooves 23 are rounded to provide the necessary clearance for the locking members 11 and may serve to guide the locking members.

In operation, the pull device 22 may be actuated in the usual manner when the upward component of a diagonal pull tends to raise the entire slider instead of only one end thereof. When the pull is grasped between the thumb and finger, and the thumb and finger pressed against the surface of the slider on each side of the pull longitudinally thereof, the movement of the slider

will be smoother since the steadyng action of the thumb and finger against the surface of the slider lessens chatter of the locking members passing through the channels and lessens any tendency to side twist or jerk.

- With the sliders of the patents referred to, difficulty was encountered in finding a suitable location where the statutory patent markings may be placed. The stringers 10 were unsuitable because if affixed in ink such markings became fugitive on washable goods and in many instances could not be seen because the stringers are secured beneath the sides of the slit to be closed by the fastener. 15 The lower or inner face of the slider is open to the objection of being of limited area and not plainly visible for the imprint of the necessary markings, but with a rigid pull device of flat material of the type shown 20 such markings may be placed on either or both sides thereof.

In Figures 5 and 6 is shown a slider corresponding to that shown in Figs. 1 and 2 except that the rivet head 24 is more elongated. Grooves 25 permit limited shifting 25 of the point of application of the actuating force in the rivet head.

Figure 7 shows the form of blank stamped from sheet metal and before being bent back 30 on itself to form the slider shown in Figs. 1, 2, 5 or 6.

Among the advantages of this invention may be enumerated its simplicity and rigidity of construction whereby the slider body 35 and wings are stamped from a single sheet which also contains the spacer portions 17. The rivet clamps the wings against the spacers and also prevents spreading of the wings. The rivet is located between the spacers referred to and enables the pull device to be 40 secured in substantially the central part of the slider. This invention provides a rigid slider of minimum overall thickness, wherein the pull will naturally lie flat below the 45 top of the rivet. This permits the slider on washable articles to pass readily through a wringer without damage, and also does not provide objectionable projections on articles equipped with this slider. Securing the pull in about the center of the slider permits a 50 diagonal actuating force to have a component tending to lift the body of the slider instead of only an end thereof to produce smoother travel of the slider. Another feature contributing to smoother travel and 55 resulting from the location of the pull device intermediate the end portions of the slider is the provision of the supporting surfaces on each side of the pull longitudinally 60 of the slider whereby the thumb and finger of the operator may rest against these supporting surfaces to steady the travel of the slider and lessen the tendency to jerks and chatter in its movement. The elongated 65 rivet head 24 of Figs. 5 and 6 provides a

very rigid construction for the slider and pull attachment and permits limited travel of the pull relatively to the center of the slider, which will be desirable in large sliders for heavy work.

It will thus be seen that the slider of this invention comprises only three parts, the wings, neck, spacer and inturned edges being formed integral, the rivet holding these parts in fixed position and near the center of the slider whereby any tendency of the diverging channels to spread is reduced to a minimum and the attachment of the pull device to the rivet head completes the slider.

This slider is especially adapted for fasteners attached to purses, bags, tobacco pouches, garments, and others, and is in short applicable to any fastener where it is convenient to hold the pull in such manner that the slider is supported by the fingers to retain its position parallel with the interlocking plane of the fastener. The transverse pivotal attachment of the pull facilitates travel of the slider around corners.

I claim:

1. A slider comprising wings forming diverging channels, means holding the wings against spreading, and a pull device pivoted between the channels adjacent one wing to confine the actuating force to substantially the intermediate portion of the slider.

2. A slider comprising connected wings forming diverging channels, means holding the wings against spreading, and a pull device transversely pivoted between the channels adjacent one wing to confine the actuating force to substantially the intermediate portion of the slider.

3. A slider comprising wings forming diverging channels, means engaging the wings between the channels to prevent spreading, and a pull device pivoted to said means to confine the actuating force to substantially the intermediate portion of the slider.

4. A slider comprising wings forming diverging channels, means engaging the wings between the channels to prevent spreading, and a pull device transversely pivoted to said means to confine the actuating force to substantially the intermediate portion of the slider.

5. A slider comprising wings forming diverging channels, means engaging the wings between the channels to prevent spreading, means between the channels to maintain spacing of the wings, and a pull device pivoted adjacent one wing to confine the actuating force to substantially the intermediate portion of the slider.

6. A slider comprising wings having inturned edges forming diverging channels, a clamping rivet passing through said wings between the channels, and a pull device pivoted to said rivet.

7. A slider comprising wings forming di-

verging channels when bent near each other, a rivet through said wings securing them together, and a pull device having a surface adapted to receive markings, pivotally secured to the rivet.

8. A slider comprising wings forming diverging channels, means holding the wings against spreading, and a pull device pivoted adjacent one of the wings near the intersection of the channels and at about the central portion of the slider laterally and longitudinally.

9. A slider comprising wings formed to provide diverging channels, and an elongated clamping member passing through perforations in the wings comprising connected ends extending longitudinally of the slider between the sides and engaging the respective external wing faces to prevent spreading.

10. A slider comprising wings formed to provide diverging channels, means externally engaging the wings between the sides and extending longitudinally of the slider to prevent spreading, and a pull device pivoted to said means and having limited movement longitudinally thereof to confine the actuating force to substantially the intermediate portion of the slider.

11. A slider comprising wings having in-turned edges forming diverging channels, a rivet passing through said wings between the diverging channels and closely adjacent their vertex, and a pull secured to said rivet below the axis of said rivet, and at about the center of the slider.

12. A slider comprising wings having in-turned edges forming diverging channels, a rivet passing through said wings and having a head provided with a recess, and a pull pivoted in said recess.

13. A slider comprising wings having in-turned edges forming diverging channels, a rivet passing through said wings and having a head provided with a groove extending lengthwise of the slider, and a pull secured within the rivet head groove.

14. A slider comprising a blank bent double and having overlying wings shaped to provide diverging channels, a portion of said blank being bent to lie between said wings and form an inner wall for one of said channels.

15. A slider comprising wings formed to provide diverging channels, a rivet passing through said wings between the channels adjacent their vertex and provided with guide grooves therein through which lock-

ing members are adapted to pass, and a pull pivoted to said rivet.

16. A slider comprising wings forming diverging channels and connected between said channels by a neck, side portions of said neck being bent down to form inner walls for said channels.

17. A slider blank comprising wings at opposite ends thereof, a neck portion connecting said wings, and a spacer portion extending from one side of said neck portion.

18. A slider comprising wings forming diverging channels and connected between said channels by a neck, side portions of said neck being bent down to form inner walls for said channels, and a rivet passing through said wings adjacent the vertex of said channels and between the inner channel walls formed by said bent side portions.

19. A slider comprising wings forming diverging channels and connected between said channels by a neck, side portions of said neck being bent down to form inner walls for said channels, and a rivet passing through said wings, and having a wedge shaped cross section with the point of the wedge at the vertex of said channels.

20. A fastener comprising a pair of continuous flexible stringers, edgewise interlocking members secured along adjacent edges of each stringer, a slider controlling the engagement and disengagement of said interlocking members comprising wings forming diverging channels, means holding the wings against spreading, and a pull device pivoted adjacent one of the wings near the intersection of the channels and at about the central portion of the slider.

21. A slider comprising stiffened wings forming diverging channels, a pull device, and means passing through the wings in the intermediate portion of the slider adjacent the channel intersection to prevent spreading, and to which said pull device is transversely pivoted.

22. A slider comprising stiffened wings forming diverging channels, a transversely pivoted pull device, and a pull device attaching means shaped to permit limited longitudinal movement of said pull device, and passing through the wings in the intermediate portion of the slider adjacent the channel intersection to prevent spreading.

Signed at Meadville in the county of Crawford, and State of Pennsylvania this 4th day of May A. D. 1923.
